UNITED STATES PATENT OFFICE.

WINIFRED BANNON, OF JOLIET, ILLINOIS.

DESIGN FOR A DOLL.

60,638.

Specification for Design. Patented Mar. 21, 1922.

Application filed October 6, 1921. Serial No. 505,936. Term of patent 7 years.

To all whom it may concern:

Be it known that I, WINIFRED BANNON, a citizen of the United States, residing at Joliet, in the county of Will and State of Illinois, have invented a new, original, and ornamental Design for a Doll, of which the following is a specification, reference being had to the accompanying drawing, forming a part thereof.

Fig. 2 is a side view of a doll embodying my invention.

I claim:

The ornamental design for a doll substantially as shown.

WINIFRED BANNON.
